UNITED STATES PATENT OFFICE.

HENRY ALFRED PORTER, OF LOS ANGELES, CALIFORNIA.

SWAB.

Application filed March 16, 1926. Serial No. 95,005.

This invention relates to the oil well industry and it relates particularly to a swab adapted for use in this industry.

The principal use for a swab of the character of my invention is for removing fluid, such as rotary mud which is employed during the drilling, from a well. When the well is drilled, a drill pipe is extended into the well having a bit at the lower end thereof, this drill being rotated by a rotary table at the surface of the ground. For the purpose of removing the cuttings of the bit from the bottom of the hole and elevating them to the surface of the ground for reinforcing the walls of the well and for preventing a premature flow of oil, rotary mud is pumped through the drill pipe to the bottom of the well, this rotary mud passing upwardly through the well to the surface of the ground outside the drill pipe. When it is desired or advisable to remove this rotary mud or other fluid from the well, it is common practice to lower into the well a swab which consists of a packer having valve means which permits the swab to be lowered through the casing. When the swab is elevated, the valve is closed and the liquid above the packer is pulled upwardly above the swab.

It is an important object of this invention to provide a swab of this character which is so constructed that it cannot elevate an overload of fluid from a well.

Another object of this invention is to provide a swab in which all the parts thereof which are subjected to wear are reversible in position; therefore, the life of the swab is substantially doubled.

A still further object of this invention is to provide a swab which is specially constructed for simplicity of parts, assembling and dismantling, and ruggedness.

Other objects and advantages of the invention will be made evident hereinafter.

Referring to the drawing in which I illustrate my invention,

Fig. 1 is a vertical section through a swab showing the different parts thereof in the positions they occupy during the lowering of the swab into the well.

Fig. 2 is a section similar to Fig. 1 showing the position of the parts during the raising of the swab and the elevating of fluid from a well.

Fig. 3 is a fragmentary view showing the position of certain parts of the swab when it is overloaded.

Fig. 4 is a section taken on the line 4—4 of Fig. 1.

The form of the invention shown in the drawing consists of a stem 11 having a head 12 formed at the upper end thereof, this head 12 having a lower shoulder 13 and a threaded pin 14. The threaded pin 14 is provided for the purpose of attaching the swab to the lower end of a pipe or connector 60 of a cable such as may be used for lowering and raising the swab in a well. The stem 11 near the lower end thereof is provided with an overload valve 15 having a valve face 16. The portion of the stem 11 between 65 the shoulder 13 and the overload valve 15 is provided with longitudinally extending flutes 17 which are provided for a purpose which will be explained later.

Surrounding the fluted portion of the stem 75 11 is a sleeve 18, the central part of which is provided with a number of openings 19. Screwed to the upper end of the sleeve 18 is an upper nut 21 which when the sleeve 18 is in upper position, as shown in Fig. 1, 80 engages the lower shoulder 13 of the head 12. The nut 21 is provided with a chamber 23 which communicates with the opening through the sleeve 18 and has apertures 24 in the wall thereof, which communicate with 85 the chamber 23 and the exterior of the nut so that there may be a passage of fluid into the opening of the sleeve 18 even through the upper nut 21 is in engagement with the lower shoulder 13 of the head 12. Screwed 90 to the lower end of the sleeve 18 is a lower nut 25.

Rigidly held between the upper and lower nuts 21 and 25 is a packer assembly indicated at 27. This packer assembly consists 95 of end members 28 which are substantially identical in construction. The outer faces of the end members are engaged by adjacent faces of the upper and lower nuts 21 and 25. Extending between the end members 28 is 100 a tube 30, the ends of which extend onto cylindrical faces 31 of the end members 28. The tube 30 is provided with a number of openings 32. Also extending between the end members 28 and surrounding the tube 105 30 is an expandable rubber packer 33, the ends 34 of which are reduced in size and extend inside cylindrical lips 35 of the end members 28, whereby the rubber packer 33 is stably secured in place.

A bottom valve 34^a surrounds the lower end of the stem 11, the bottom valve 34^a

having a passage 35^a formed therethrough through which the lower end of the stem 11 extends. The central part of the passage 35^a is connected to the exterior of the bottom valve 34^a by means of a plurality of radially extending openings 36. The valve member 34^a is made symmetric in its upper and lower parts having an upper and a lower seat 37 which are identical, and having an upper and a lower valve face 38 formed on an annular ridge 39, which are likewise identical. The lower end of the bottom valve 34^a is engaged by a washer 40 which surrounds the lower end of the stem 11, this washer 40 having a tubular extension 41. The lower end of the stem 11 is threaded, as shown in the drawing, and a nut 42 having a tubular projection 43 is advanced on the lower end thereof, being locked in place by a lock nut 45. As a further means of holding the nut 42 and also the lock nut 45 on the stem, a pin 46 is extended through the extreme lower end of the stem 11. Compressed between the washer 40 and the nut 42 is a coil spring 48 which likewise surrounds the lower end of the stem 11. The purpose of the spring 48 is to resiliently hold the upper of the seats 37 in engagement with the valve face 16 of the overload valve 15 at all times unless there is an overload imposed on the swab.

In Fig. 1 the sleeve 18, and of course the packer assembly 27, is shown in raised position and in Fig. 2 the sleeve and packer assembly is shown in lowered position. It is pointed out that when the sleeve is in lowered position a seat 49 formed at the lower end of the bottom nut 25 engages the upper of the valve faces 38 of the bottom valve 34^a. When in this position an enlarged opening 51 which communicates with the opening through the sleeve 18 is closed.

The operation of my invention is substantially as follows:

The swab is connected to the lower end of a cable line by means of which it is lowered into a well from which it is desired to remove fluid. By friction of the packer on the casing of the well or friction of the fluid the packer assembly 27 is moved into the position shown in Fig. 1 so that the upper nut 21 engages the shoulder 13 of the head 12. This removes the bottom valve 34^a from engagement with the seat 49 of the lower nut 25 and therefore opens the opening through the sleeve 18. This permits the swab to be easily lowered, since the fluid displaced may flow through the sleeve 18 to a point above the swab. When the depth is reached from which the fluid is to be raised, the cable to which the swab is secured is pulled upwardly. The packer unit 27 by reason of friction is immediately lowered into the position shown in Fig. 2 and in a position to seat the bottom valve 37

and to close the opening through the sleeve 18 so that there can be no passage of fluid therethrough. Upon the initial upward movement of the swab the pressure therebelow is reduced, and pressure of the fluid thereabove causes the expansible rubber packer 33 to expand into a position indicated by dotted lines 53 of Fig. 2.

Referring to Fig. 2 the fluid is at liberty to flow through the openings 19 in the sleeve 18 into a space 54 formed between the sleeve 18 and the tube 30. This fluid exerts an outward pressure on the expansible rubber packer 33 through the openings 32 in the tube 30. For this reason, as the swab is elevated the packer will be expanded into this position shown by dotted lines 53 of Fig. 2. This causes the packer to frictionally engage the inner walls of the casing of the well and therefore the swab acts as a plunger of a reciprocating pump. The swab is elevated to the upper end of the well and the fluid situated thereabove is pulled upwardly therewith and is taken from the top of the well casing. The swab of my invention may be set to carry a certain load of the fluid and if it is attached to elevate more than this load, the parts will operate in a manner to open the opening through the sleeve 18. For example, if the swab is lowered below a certain distance the fluid thereabove will be of too great a load for the swab to lift. When the swab moves upwardly the pressure of this load on the packer assembly 27 will be sufficient to move the packer assembly 27 downwardly relative to the stem 11 and against the action of the coil spring 48, the parts moving into the position illustrated in Fig. 3. At this time the bottom valve 34^a is moved downwardly out of engagement with the valve face 16 of the overload valve 15. This unseating of the overload valve 15 communicates the passage 35^a of the bottom valve 34 with the enlarged opening 51 of the bottom nut 25 and with the sleeve 18. This permits the fluid above the swab to flow through the sleeve 18 to a point below the swab as it is elevated. As the load on the swab decreases, the reaction against the coil spring 48 decreases and the valve 15 will gradually approach its seat 37. When the weight of the fluid on the swab decreases to a maximum load intended to be carried thereby, the valve 15 will seat and the fluid will then be elevated to the surface of the ground.

By an adjustment of the nut 42 the resilient pressure tending to seat the overload valve 15 may be varied so that the swab may be caused to carry any load desired.

One important feature of my invention is that the swab is of simple construction and that the parts thereof are rugged. The stem 11 is made but slightly smaller than the opening through the tube 18 for the pur-

pose of strength. To give the opening through the tube 18 sufficient capacity, the stem 11 is provided with the flutes 17. The large stem with the flutes 17 is stronger than 5 a smaller stem having no flutes therein. Another important feature of the invention is that all of the parts which are subjected to wear are reversible in position. The packer asesmby 27, the expandible rubber 10 packer 33 of which is subjected to wear, may be inverted by merely removing the lower nut 25 and inverting it in position. The bottom valve 34^a, as previously explained, is made symmetric in its upper and lower 15 halves and when wear takes place thereon, it may be inverted, thus renewing the faces thereof which are subjected to wear. This is a desirable feature, since there are only a few parts of the packer which are subjected to any material wear. In ordinary 20 packers it is necessary to replace the worn parts. This is expensive since some of the parts which are subjected to wear are quite large and cost considerable. In my invention 25 there is, therefore, an appreciable saving and an exceedingly great amount of convenience.

I claim as my invention:

1. In a swab of the class described, the 30 combination of: a stem; a head near the upper end of said stem; a sleeve surrounding said stem below said head; an upper nut attached to the upper end of said sleeve, said upper nut being adapted to engage said 35 head when said sleeve is in raised position;

a lower nut attached to the lower end of said sleeve; a packer assembly secured on said sleeve between said upper and lower nuts; an overload valve formed on said stem; a bottom valve surrounding said stem 40 below said overload valve, said bottom valve engaging a seat of said lower nut when said sleeve is in lowered position for closing the opening through said sleeve; and means for resiliently holding a face of said bottom 45 valve in engagement with said overload valve unless said swab is overloaded, said overload valve closing a passage through said bottom valve.

2. A combination as in claim 1 in which 50 said means includes a spring urging said bottom valve, and surrounding the lower end of said stem.

3. A combination as in claim 1 in which 55 said packer assembly is reversible in position on said sleeve.

4. A combination as defined in claim 1 in which said stem is but slightly smaller than said sleeve and is provided with flutes to increase available opening through said 60 sleeve.

5. A combination as defined in claim 1 in which said bottom valve is symmetric in its upper and lower halves so that it may be 65 used in inverted position on said stem.

In testimony whereof, I have hereunto set my hand at Los Angeles, California, this 10th day of March, 1926.

HENRY ALFRED PORTER.
